SURVIVAL LAMP OR SIMILAR ARTICLE

David T. McArthur, Santa Ana, Calif., assignor to Survival Oriented Systems Company, Corona Del Mar, Calif.

Filed June 8, 1971, Ser. No. 151,167

Term of patent 14 years

Int. Cl. D26—02

U.S. Cl. D48—24

FIG.1

FIG.4

FIG. 1 is a perspective view of a survival lamp or similar article showing my new design.

FIG. 2 is a side elevational view thereof.

FIG. 3 is a top plan view thereof.

FIG. 4 is a bottom plan view thereof.

The side opposite that shown in FIG. 2 is substantially similar to that shown.

I claim:

The ornamental design for a survival lamp or similar article, as shown and described.
